UNITED STATES PATENT OFFICE.

FREDERICK F. HODGES, OF KALAMAZOO, MICHIGAN.

HAME AND TRACE CONNECTION.

1,125,533.

Specification of Letters Patent.

Patented Jan. 19, 1915.

Application filed July 27, 1910. Serial No. 574,086.

To all whom it may concern:

Be it known that I, FREDERICK F. HODGES, a citizen of the United States, residing at Kalamazoo, Kalamazoo county, Michigan, have invented certain new and useful Improvements in Hame and Trace Connections, of which the following is a specification.

This invention relates to improvements in hame and trace connections, and is a species of my invention appearing in my patent bearing date November 9, 1909, No. 939,420, for hame and trace connection.

The object of this invention is to provide a structure especially designed to be economically produced from sheet metal stampings, and to provide a coupling which will operate with a minimum wear on these important parts of a harness.

20 A further object is to provide improved attachment to the tug.

Objects pertaining to details will be readily understood from the detailed description to follow.

25 I accomplish the objects of my invention by the devices and means described in the following specification.

The invention is clearly defined and pointed out in the claim.

30 A structure embodying the features of my invention is clearly illustrated in the accompanying drawings, forming a part of this specification, in which:

Figure 1 is a side elevation view, substantially full-sized, of my improved hame and trace connection. Fig. 2 is a detail, longitudinal, horizontal, sectional view through the same, taken on line 2—2 of Fig. 1. Fig. 3 is a further detail view, with portions 40 broken away to show the stop on the swivel loop member and its relations to the other parts of the device. Fig. 4 is a detail sectional view, taken on line 4—4 of Fig. 1, looking upwardly, showing details of connection to the tug straps. Fig. 5 is a detail view of the blank from which the connecting loop is formed. Fig. 6 is a detail view of the blank from which is made the part 12 of the connection formed between the swivel 45 loop 10 and trace 11. Fig. 7 is also a detail view of the part 13, of the connection between the swivel loop 10 and trace 11. Fig. 8 is a detail view similar to Fig. 3 showing a modification of the stop.

50 In the drawing similar numerals of ref-

erence refer to similar parts throughout the several views.

Considering the numbered parts of the drawing, a portion only of the hame 1 is illustrated, on which is the usual reinforcing iron 2. Into this are inserted the pair of eyes 3, through which extends the pivot bolt 4. The structure I illustrate is a hame structure with a bolt pivot, but the structure, of course, is adapted to those hames in which a staple is made use of.

My especially constructed clip 5 has an open space 5' at the center and has fingers 6,—see Figs. 1, 3 and 5—which embrace the pivot bolts 4 toward each end, just within the eyes 3. This makes a comparatively narrow, tubular embracing ring at each end. Within this open space 5' is formed a U-shaped loop clip 7, integral with the said part 5. I insert a rivet 8 through this part 75 and also through the head of the swivel loop 10. This rivet has a square shank part 9, which fits into a square hole 9' in the clip 5, which prevents its rotation, for I find that, where the pivot is round, it is rotated 80 with the head and rapidly wears the clip. I provide a stop 15 on the swivel 10, arranged to contact with the pivot and limit movement of the parts. This avoids disarranging the harness. I show a modification 85 of this stop means in Fig. 8, where a stop 16 contacts with the finger 6 for the same purpose.

In the swivel loop 10, I secure the trace 11 by suitable clip pieces. The piece 12 has 90 parallel fingers 12' and is secured by rivet 14 to the outer side of the trace, and the fingers 12' are wrapped around the pivot part of the eye. The inner hinge piece 13 is folded upon itself to form an eye,—see 95 Fig. 1—and the parts folded upon themselves are centrally located between the layers of the trace 11 and are joined thereto by the rivet 14, and any additional rivets that may be desired at this point. A very 100 strong metallic connection, very simple to manufacture, is thus produced.

The structure of the clip member here produced differs from that in my former patent in that the clip piece 5 is a single 105 piece, the structure being satisfactorily produced in this form at a considerable saving of metal and labor.

The method of connecting the tug to the swivel loop might be any of the well known 110

connections now in use, such as a link or ring, although I think I have simplified and improved this connection also, and desire to claim the improvements that I have produced. The loop 10 can be adapted to any tug connection by varying its size or shape.

Having thus described my invention, what I claim as new and desire to secure by Letters Patent is:—

13. In a hame and trace connection, the combination with the pivot bolt of a hame, of a sheet metal clip having embracing fingers wrapped completely around the said pivot

forming eyes toward each end thereof, an intermediate U-shaped loop integral therewith, and a swivel secured within the said intermediate loop by a suitable cross rivet, coacting for the purpose specified.

In witness whereof, I have hereunto set my hand and seal in the presence of two witnesses.

FREDERICK F. HODGES. [L. s.]
